UNITED STATES PATENT OFFICE.

JAMES H. YOUNG, OF TROY, NEW YORK.

METHOD OF MAKING APPAREL-COLLARS.

SPECIFICATION forming part of Letters Patent No. 371,723, dated October 18, 1887.

Application filed May 23, 1887. Serial No. 239,065. (No model.)

To all whom it may concern:

Be it known that I, JAMES H. YOUNG, of the city of Troy, county of Rensselaer, and State of New York, have invented a new and useful 5 Improvement in Apparel - Collars, of which the following is a specification.

My invention relates to apparel-collars; and it has for its object an improvement of the manner and method of cutting and arranging 10 the facings of the collar and the intermediately-placed ply or filling to insure the permanent attachment of the parts, so that the interior ply will not become free at its edges and bunch up during the operation of laundering.

15 My invention consists in the improved method of forming and securing the ply or filling of an apparel-collar and the other parts together, as follows: I cut from the fabric a ply-blank of substantially twice the size of the 20 collar in length and width, and of the form substantially as shown in Figure 1 of the drawings. This ply-blank is then folded longitudinally in the middle to produce two thicknesses 25 of ply. The collar-blanks are then cut in the form and placed between the plies, with the outer edges of the facings abutting the fold-line of the plies, and the parts so arranged sewed along the fold-edge of the ply and inserted 30 facings and at the ends of the collar, as seen in Fig. 2 of the drawings. The blanks are now turned through the unsewed bottom opening, to bring the facings on the outside. The 35 edges of the bottom are then turned in, and the collar completed by a line of stitches extending entirely about its edges, as seen in Fig. 4 of the drawings.

Accompanying this specification, to form a part of it, there is a sheet of drawings containing five figures illustrating my invention, 40 with the same designation of its parts by letter-reference used in all of them.

Of the illustrations, Fig. 1 shows a plan view of the ply-blank with its longitudinal fold-line indicated by a dotted line. Fig. 2 45 illustrates the ply-blank as folded longitudinally, so as to embrace the two facings, and showing a line of stitching made along the fold-line to embrace the outer edge of the facings. Fig. 3 shows a cross section of the parts illustrated at Fig. 2, taken on the line $\alpha' \alpha'$ of Fig.

2. Fig. 4 shows the completed collar, and Fig. 5 a cross-section of the same, taken on the line $\alpha^2 \alpha^2$ of Fig. 4.

The several parts of the collar thus illustrated are designated by letter-reference, and 55 the function of the parts is described as follows:

The letters P indicate the ply-blank, which is cut in one piece, so that when folded longitudinally at d , as indicated by the dotted line of Fig. 1, it forms two thicknesses of the ply 60 or filling designated at $p' p^2$, one edge of the ply-blank being cut with tab ends t' , and the other edge without them.

The letters F' F² designate the exterior facings of the collar, on each end of which are 65 formed the tab ends t^2 .

The parts are connected as follows: The longitudinal fold d being made in the ply-blank P, there are produced the two ply thicknesses $p' p^2$. Between the latter are placed the two 70 facings F' F², with their surfaces together, and their upper edges, e' , close up within the ply-fold made at d , as shown at Figs. 2 and 3. With the parts thus placed, a line of stitching, S', is run along the upper edge of the collar, 75 passing through the embracing-folds of the ply and the intermediately-placed upper edges of the facings and the end edges of the facings and ply, as indicated at S', and around the tab ends, as at S². After this has been done then 80 the attached parts are turned through the open bottom B, so as to bring the facings F' F² to the outside. Then the downwardly subtending bottom edges of the facings are turned in and the collar is closed at the bottom edge by 85 the seam S', after which the whole collar-body is border-stitched, as indicated at S². As thus made the ply is securely anchored to the facing at the edges, and so that it cannot become loosened in laundering. If desired, both of 90 the end edges of the double ply-blank may be cut without tab ends, or tab ends may be cut upon both of the end edges of the double ply-blank.

Having thus described my invention, what I 95 claim, and desire to secure by Letters Patent, is—

The method herein described of making and completing an apparel-collar, which consists in cutting a ply-blank of fabric of substantially 100

twice the size of the collar, then folding said blank in the longitudinal middle, then inserting the collar or facing blanks within the folded 5 ply-blank with their edges abutting the fold-line thereof, then securing all of said blanks together by a line of stitches through the fold-line and at the ends, then turning the facings to the outside, and then turning the bottom edges in, and then securing the parts by a line

of stitches about the entire edges of the collar, 10 substantially as specified.

Signed at Troy, New York, this 1st day of April, 1887, and in the presence of the two witnesses whose names are hereto written.

JAMES H. YOUNG.
